UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS.

MOTOR AND EXHAUST APPLIANCE FOR PIANO-PLAYERS.

1,190,379.

Specification of Letters Patent. Patented July 11, 1916.

Application filed April 29, 1914. Serial No. 835,111.

To all whom it may concern:

Be it known that I, MELVILLE CLARK, a citizen of the United States, residing at Chicago, in the county of Cook and State of Illinois, have invented new and useful Improvements in Motor and Exhaust Appliances for Piano-Players, of which the following is a specification, reference being had to the accompanying drawings, forming

a part thereof.

The purpose of this invention is to provide an improved exhaust appliance for operating the pneumatic action of a player piano particularly adapted for service in connection with a grand piano having automatic player mechanism within its case, in view of the deficiency of inclosed space in the usual construction of grand pianos adequate to accommodate the necessary exhaust devices and pumping devices without disfigurement of the piano as a whole.

It consists in the elements and features of construction shown and described as indicated in the claims.

In the drawings: Figure 1 is a side elevation of a grand piano having associated with it the structure embodying this invention comprising the player's bench, the latter being shown in vertical longitudinal section, at the line, 1—1, on Fig. 3. Fig. 2 is a plan view of the same, a portion of the piano being broken away to reduce the view in one dimension. Fig. 3 is a top plan view of the player's bench and contents, the top which forms the seat being folded back to disclose the mechanism contained in the bench. Fig. 4 is a detail section at the line, 4, 4, on Fig. 3. Fig. 5 is a detail view of the coupling for the air trunk. Fig. 6 is a detail view of a swivel joint in the air trunk. Fig. 7 is a detail view of the two members of the coupling for connecting the circuit wires of the electric motor of the piano case.

As is well known, the space inclosed within the case and frame work of a grand piano, as ordinarily constructed, is not suitable for receiving exhaust devices comprising pumping mechanism and a motor or pedals for operating the same, and these parts of an automatic player mechanism when associated with a grand piano have heretofore been necessarily mounted in such position

as to involve more or less disfigurement either by reason of extended casing to inclose them, or leaving them uninclosed and visible. This objection is overcome in the construction herein shown, in which pumping devices and motor for the same are inclosed in a player's bench of the usual dimensions of such bench, and differing from the ordinary bench only in being inclosed below the seat and within the supports so as to constitute a chest or box instead of a skeleton as is more usual.

In the drawings the grand piano casing, A, of usual form, may be understood to contain the pneumatic action for operating upon the keys and to have the tracker box comprising the rolls and roll-operating mechanism mounted in any desirable position for sliding or swinging into and out of operative position, being at its operative position projected beyond the vertical line of either the front or one of the straight edges of the piano casing. As illustrated, it is shown at the longer side of the piano, being represented in operative position in Fig. 2. The player's bench, B, consists, as stated, of a box or chest having the top, B¹, hinged at the rear edge to a top rail, B², of the rear side, said rear side having a portion, B³, intermediate the top rail, B², and the bottom rail, B⁴, preferably to afford easy access at that side to the mechanism. The forward wall of the bench has a panel, B⁵, at the upper part hinged at its upper edge to the lower portion, B⁶, of said forward wall, for opening outward and downward, as shown in Fig. 4, to open the front of the bench over its whole length at the front and upper part, for a purpose which will hereinafter appear.

Within the bench mounted upon its floor, B⁷, which is up-raised from the floor on which the bench and piano stand sufficiently to permit finishing the bench at the bottom so as to cause it to present the appearance of legs or feet at the four corners, there are mounted the several parts of the mechanism comprising an electric motor, C, and pumps, D, D, which are operated by the motor through the medium of a counter-shaft, E¹, mounted on a bracket or chair, E, said counter-shaft having two belt pulleys, F and F¹, the first of which is driven by a belt, G,

from the pulley, C¹, of the motor, while the second, F¹, drives by means of a belt, G¹, a pulley, H, on the pumper crank-shaft, h. Both pumpers are connected with the trunk chamber, J, for exhausting the same through a trunk pipe, K, which is mounted upon the top of the trunk chamber, the parts being proportioned so that at that position it is a few inches below the lid or top, B¹, of the bench. A swivel elbow fitting, L, connects the trunk pipe, K, with the out-leading trunk, M, which is designed for connection with the exhaust chamber of the pneumatic action mounted on the piano casing, and not shown, but of which the trunk connection, N, is shown mounted on the under side of the piano casing by means of a hanger, N¹, and terminating in one member, N², of a coupling of which the mating member, M², is the terminal of the trunk, M. By arranging the several parts so that the trunk pipe, M, leads out from near the top and one end of the bench, and so that there is unoccupied space in the bench under the lid along the whole length of the bench at the upper forward part, and providing a suitable connection, L, as described, it is possible to accommodate the trunk, M, when disconnected from the trunk member, N, on the piano wholly within the inclosed space of the bench; and by providing the hinged panel, B², swinging downwardly as shown, the trunk member when disconnected at the coupling, M², N², from the member, N¹, may be readily swung around into the gravity of the bench and concealed by closing up the hinged panel, B².

The connection, indicated diagrammatically by the circuit wires, v—v, on Fig. 2, from any source of electric energy for energizing the motor, C, is desirably controlled by the operator by means of a manually-operable stop device of some sort, shown conventionally at M⁴, mounted in the usual position on the tracker box, but it is necessary to provide connection from the piano casing to the player's bench for bringing the motor into the circuit. For this purpose the in-leading and out-leading wires, X and Y, from the motor binding posts, are united in a cable, Z, which is coiled around to the trunk pipe, M, so as to be carried with it in its movement from the position which is shown in dotted line in the cavity of the player's bench to the position at which the cable is connected by the coupling, M², N², to the trunk, N, and there is mounted upon the piano casing the socket member, W, of the customary coupling for the circuit wires, the co-operating member W¹ of said coupling (see Fig. 7) being connected to the cable wires, X and Y, which are cabled as seated and coiled around the trunk, M. By this means both the trunk and the electric connections are readily disconnected

from the piano and carried into the chamber of the player's bench and concealed therein, and the bench being mounted on casters, if desired, is readily movable out of the way, and if desired can be moved under the piano and in general disposed of in any position which would accommodate the ordinary player's bench.

I claim:—

1. In combination with a grand piano casing, a tracker and roll carrier mounted thereon and an automatic player action mounted therein, comprising an exhaust chamber and an air trunk leading therefrom; a casing independent of the piano casing wholly exterior thereto; exhaust pumpers and an electric motor for the same mounted in said exterior casing, an air trunk connected with the pumpers leading from said exterior casing and adapted for connection with the air trunk on the piano casing; electric circuit wires in the piano casing and a controlling key in said circuit accessible at the piano front; circuit wires connected with the motor in the exterior casing, and disengageable terminals for the circuit wires which are located in the piano casing and in the exterior casing respectively.

2. In combination with a grand piano casing, a track-and-roll carrier mounted thereon and an automatic player action mounted therein, comprising an exhaust chamber and an air trunk leading therefrom; a casing independent of the piano casing wholly exterior thereto; exhaust pumpers and an electric motor for the same mounted in said exterior casing, an air trunk connected with the pumpers leading from said exterior casing and adapted for connection with the air trunk on the piano casing; electric circuit wires in the piano casing and a controlling key in said circuit accessible at the vicinity of the tracker-and-roll carrier; circuit wires connected with the motor in the exterior casing, and disengageable terminals for the circuit wires in the piano casing and in the exterior casing respectively, the circuit wires in the exterior casing being coiled around the air trunk leading from the pumpers therein, and the air trunk terminal and circuit wire terminals in the piano casing being proximately situated on the latter.

3. In combination with a grand piano casing, a tracker-and-roll carrier mounted thereon, an automatic player action therein comprising an exhaust chamber and an air trunk leading therefrom; a player's bench comprising a chamber under the seat, the front wall of the chamber having a longitudinally-extending opening; and a movable panel for closing said opening; pumpers and operative mechanism therefor mounted in the bench chamber; an air trunk leading

from the pumbers and a swivel joint by which said trunk is connected with the pumbers for swinging about a vertical axis, said joint being located near one end of the chamber in position for swinging the trunk about said axis to carry it in horizontal path through said opening, the contents of said chamber being arranged to afford unoccupied space at the forward side in the hori-

zontal plane of said opening to accommo- 10 date the trunk therein.

In testimony whereof, I have hereunto set my hand, at Chicago, Illinois, this 10th of April, 1914.

MELVILLE CLARK.
